UNITED STATES PATENT OFFICE.

ISAAC E. PALMER, OF MIDDLETOWN, CONNECTICUT.

DESIGN FOR A HAMMOCK-VALANCE.

No. 37,765.

Specification for Design.

Patented Dec. 26, 1905.

Application filed November 23, 1905. Serial No. 288,819. Term of patent 14 years.

To all whom it may concern:

Be it known that I, ISAAC E. PALMER, a citizen of the United States, and a resident of Middletown, in the county of Middlesex and State of Connecticut, have invented a new, original, and ornamental Design for a Hammock-Valance, reference being had to the accompanying drawing, forming a part thereof.

My new, original, and ornamental design

for a hammock-valance is shown in the accompanying drawing.

I claim—

The ornamental design for a hammock-valance as shown.

ISAAC E. PALMER.
